UNITED STATES PATENT OFFICE.

WILLIAM LE FRANCOIS, OF PAWTUCKET, RHODE ISLAND.

VALVE.

1,345,682.

Specification of Letters Patent.

Patented July 6, 1920.

Application filed July 31, 1919. Serial No. 314,546.

To all whom it may concern:

Be it known that I, WILLIAM LE FRANCOIS, a citizen of the United States, and resident of the city of Pawtucket, in the county of Providence and State of Rhode Island, have invented certain new and useful Improvements in Valves, of which the following is a specification.

This invention relates to improvements in the construction of fluid pressure valves and has for its object to provide such a valve more particularly adapted for use as a so-called ball cock for flush tanks, the same being arranged to close the discharge opening of the inflowing pressure when resting upon the valve seat and to be moved to open position against the inflowing pressure.

A further object of the invention is to provide an elongated tapering portion on the valve extending toward the entering fluid pressure by which arrangement the pressure serves to assist in carrying the valve to and holding the same closed against its seat, the tapering portion serving to reduce the force required to open the valve against the pressure thereby insuring a tight valve and also one that can be readily operated by action of a ball float of the minimum size.

With these objects in view, the invention consists of certain novel features of construction, as will be more fully described, and particularly pointed out in the appended claims.

In the accompanying drawings:

Figure 1— is a sectional side elevation showing my improved valve as applied to a flush tank.

Fig. 2— is a detail side elevation of the valve.

Fig. 3— is an end view of the valve.

Referring to the drawings, 10 designates the ordinary flush tank which is supplied with water through the pressure pipe 11. 45 The ball cock in this construction comprises a valve body portion 12 which is connected by the coupling 13 to the pressure pipe. In this body is formed a valve seat 15 and a discharge opening 16.

50 My improved valve 17 is mounted to move endwise in this casing and is provided with a stem 18 extending back through the rear of the casing. The valve proper has a conical or tapering shaped head 19 which extends toward the entering pressure so that the fluid instead of acting against the flat

face of a disk impinges against the conical or tapering face thereof and so serves to slightly reduce its effective action upon the valve permitting it to be moved outwardly 60 or against a pressure by the exertion of less force than would be the case if the conical portion were not present.

At the base of this cone I preferably secure a leather seat 20 to insure the valve 65 being tight when resting upon its seat.

This valve may be operated by any suitable means but in Fig. 1, I have shown an arm 21 pivoted at 22 in the bracket 23 its lower end being pivotally connected to the 70 end 24 of the valve stem 18. I have also provided an upwardly extending boss 25 on this arm in which the float rod 26 is adjustably mounted, the float 27 being secured to the outer end of this rod whereby when the 75 water level in the tank is lowered the float falls and opens the valve permitting the water to again run into and fill the tank raising it to a given level, and when the tank is sufficiently full again the valve 17 80 through the action of the float 27 is moved to its seat 15 where it is held tight both by the action of the float and also by the pressure of the water against it.

It is found in practice that an endwise 85 movable valve having a cone shaped portion extending toward the inflowing pressure has a number of advantages; first, the pressure serves to assist in carrying the valve to its seat and holding it tight thereon, and second, that a much smaller ball is required to operate the valve to open it against the pressure than what would be required when the valve is constructed without the tapering portion.

95 The device is extremely simple and practical in construction and by its use the water pressure serves to carry the valve to its seat and hold it tight and the valve is easily operated.

100 The foregoing description is directed solely toward the construction illustrated, but I desire it to be understood that I reserve the privilege of resorting to all the mechanical changes to which the device is 105 susceptible, the invention being defined and limited only by the terms of the appended claim.

I claim:

110 A ball cock comprising a valve casing having a pressure inlet opening a seat and a discharge opening, and endwise movable

valve in said casing having a seat portion, a conically-shaped end member on said seat portion extending toward the entering pressure fluid and of a length approximately 5 two and one-half times the diameter of said seat portion to reduce the operating resistance of said valve when moved against the pressure, a stem on said valve, and a lever arm pivotally connected between its ends to 10 said casing and having one end pivotally

connected with said stem to positively control both the opening and closing movements of said valve.

In testimony whereof I affix my signature in presence of two witnesses.

WILLIAM LE FRANCOIS.
